UNITED STATES PATENT OFFICE

117,626

DESIGN FOR A TRAWLER OR THE LIKE

Isidore Bromfield, Waban, Mass.

Application February 27, 1939, Serial No. 83,233

Term of patent 14 years

To all whom it may concern:

Be it known that I, Isidore Bromfield, a citizen of the United States, residing at Waban, in the county of Middlesex and Commonwealth of Massachusetts, have invented a new, original, and ornamental Design for a Trawler or the like, of which the following is a specification, reference being had to the accompanying drawings forming a part thereof.

In the accompanying drawings, Figure 1 is a view, in side elevation, of a trawler showing my new design, its hull, masts and deck rails being indicated by dotted lines in order to completely disclose the superstructure, and its masts being broken off for convenience in delineation; Fig. 2 is an enlarged plan view of the trawler as shown

in Fig. 1, the hull being broken and shortened, as shown by the dotted lines; and Figs. 3 and 4 are front and rear views, respectively, of the pilot house at the forward end of the superstructure.

The dominant feature of my design is shown in the drawings by the full lines delineating the superstructure, the dotted lines indicating the conventional hull and masts of a trawler.

My design is delineated as embodied in the superstructure of a trawler but my design may also be embodied in or applied to other superstructures of like nature.

I claim:

The ornamental design for a trawler or the like, substantially as shown and described.

ISIDORE BROMFIELD.
